UNITED STATES PATENT OFFICE.

WILLIAM H. HOLLAR AND ALONZO L. RHODES, OF PHILADELPHIA,
PENNSYLVANIA; SAID RHODES ASSIGNOR TO SAID HOLLAR.

ELECTRICALLY-CONTROLLED WINDING MECHANISM FOR TIME-LOCKS.

SPECIFICATION forming part of Letters Patent No. 650,842, dated June 5, 1900.

Application filed March 10, 1899. Serial No. 708,480. (No model.)

To all whom it may concern:

Be it known that we, WILLIAM H. HOLLAR and ALONZO L. RHODES, of Philadelphia, in the State of Pennsylvania, have invented a 5 certain new and useful Electrically- Controlled Winding Mechanism for Time-Locks, whereof the following is a specification, reference being had to the accompanying drawings.

It is the object of our invention to provide 10 means to wind the clock-movements of time- locks such as are employed upon safes, vaults, &c., without opening the latter, such a device being particularly useful to rewind said movements in any emergency in which it is desirable 15 to postpone the moment of opening originally predetermined by the set of the time mechanism when the safe or vault was locked.

Letters Patent of the United States Nos. 545,020 and 545,021 have been granted to 20 William H. Hollar *et al.* for devices of the type aforesaid; and our present invention comprises an improved construction and arrangement of means whereby a plurality of clock - movements may be simultaneously 25 wound by a normally - disconnected motor through winding mechanism adapted for independent connection to the respective movements, as hereinafter more definitely specified.

Generally stated, the main features of our 30 invention comprise the combination, with a safe or vault, of a time-lock therefor having a plurality of clock-movements, any one of which is designed to effect or permit of the release of the lock after a predetermined interval; winding mechanism adapted for independent connection with the respective movements, but normally disconnected therefrom, and a motor adapted to actuate said winding mechanism and controlled by means 35 exterior to the safe or vault.

Our present improvements are applicable 40 to any ordinary form of time-lock and, although we shall for convenience refer to certain parts of our invention as "rewinding mechanism" to distinguish the same from the manually-operative winding mechanism with which said locks are ordinarily provided, it is to be understood that all of the winding or 45 rewinding operations of a time-lock may be effected by our device to the exclusion of said ordinary manually-operative mechanism.

With the foregoing main elements our invention combines certain adjuncts—such, for instance, as stop mechanism—connected with the respective clock-movements to prevent 55 the overwinding of the same by said motor by effecting the disengagement thereof at the proper instant and a device for indicating or reporting the extent to which the rewinding mechanism has been operated. 60

In the accompanying drawings, Figures 1, 2, and 3 represent, diagrammatically, three slightly-modified arrangements of electrical connections for our invention. Fig. 4 is a rear elevation of a time-lock, showing a convenient embodiment of our improvements. Fig. 5 is a sectional view taken on the line 55 in Fig. 4. Fig. 6 is a sectional view taken on the line 6 6 in Fig. 4. Fig. 7 is a sectional view similar to Fig. 5, but showing modified 70 means for engaging the rewinding mechanism with the respective clock-movements. Fig. 8 is a fragmentary rear elevation showing the application of a convenient form of stop mechanism to the rewinding mechanism shown in 75 Fig. 4. Fig. 9 is a detail view of one of the clock-movement pawl-disks. Fig. 10 is a central longitudinal sectional view of the stop mechanism shown in Fig. 8.

Referring to Fig. 1, A represents an electric motor, which, as hereinafter described, is arranged to actuate the rewinding mechanism of the time-lock. The electric generator B, indicated as a primary battery, is in circuit with the motor A through connections 85 a a, and C is a switch by which the operation of said motor is controlled.

As shown in Fig. 2, the motor A is series-wound and the circuit between said motor and the generator B, indicated as a secondary 90 battery, includes an electromagnet D, which serves, as hereinafter described, to permit the engagement of the rewinding mechanism and the respective clock-movements upon the completion of the circuit at switch C. 95

As shown in Fig. 3, the motor A is shunt-wound and connected in multiple with the electromagnet D, the generator B being indicated as a dynamo.

Referring to Fig. 4, A is the motor, (indicated, diagrammatically, in Fig. 1,) and it is to 100 be understood that the same is in circuit with

a suitable generator and provided with the necessary appurtenances, such as the switch indicated in Fig. 1.

The motor A is conveniently fixed upon the casing X of a time-lock comprising four clock-movements, respectively indicated at X', X², X³, and X⁴. Said motor A is provided with an armature-shaft A', upon which is keyed a worm A², as shown in Fig. 5. Said worm 5 engages the worm-gear A³ upon the shaft A⁴, which extends at right angles with the shaft A' and is provided with worms A⁵ A⁶ A⁷ A⁸ to respectively engage and rewind the aforesaid clock-movements X' X² X³ X⁴. The 10 rewinding mechanism comprises counterpart groups of members connecting each of said worms with its respective clock-movement. We shall therefore confine the following description thereof to a single one of said groups. 15 Referring to Fig. 6, the main arbor x³ of the clock-movement X³ is provided with a pawl-disk E, which is fixed thereon conveniently by engagement with its squared extremity. Upon said pawl-disk E is mounted 20 a pawl e, whose outer extremity e' is adapted to engage the teeth of a face-ratchet f upon the gear F, which is in constant engagement with the worm A⁷ upon the shaft A⁴, but is mounted to rotate loosely upon the hub of 25 said pawl-disk E.

It is to be understood that each of the clock-movements X', &c., comprises an independent spring which when wound progresses its respective mechanism to ultimately release the 30 usual automatic bolt mechanism at a predetermined instant. In said progress the main arbor x³ of the clock-movement X³ is rotated in the opposite direction to that required for its winding or rewinding, so that although 35 the above-described engagement of the parts of the rewinding mechanism serves to properly connect the motor A to rewind the spring of said clock-movement X³ means must be provided to disengage said winding mechanism in order to permit the aforesaid normal 40 progression of said clock-movement.

During the rewinding operation of the above-described parts the pawl e is maintained in engagement with the ratchet f by 45 means of the spring e². However, the inner end e³ of said pawl is prolonged beyond the center of rotation of the arbor x³ to be conveniently disengaged, as follows:

The frame G is mounted for oscillation in 50 the bearings g upon the casing X, and the upper bar G' thereof extends in opposition to the axes of rotation of the main arbors and disks E of all of the clock-movements. Said bar G' is provided with detents II' II² II³ II⁴ in 55 alignment with the respective axes of rotation of the disks E, so that said detents are adapted to encounter the extensions e³ of the pawls e to disengage the latter from the ratchets f when said frame G is rocked in the bearings g to the position indicated in Fig. 7. Said detents are in threaded engagement with the bar G', so as to be conveniently adjusted 60

in the primary assembling of the parts. It is to be understood, however, that said detents are in fixed relation with the frame G 70 during its operation.

In the form of our invention shown in Figs. 1, 4, 5, and 6 the frame G is normally maintained in position to disengage said pawls e by the weight of the armature A⁸ and shaft 75 A' of the motor A, resting upon the arm G² of said frame, the magnetic center of said armature being in said position slightly below the magnetic center of the motor-field. The completion of the electric circuit at switch C 80 serves not only to actuate said motor A, but also to lift said armature to the center of said field and permit the frame G to swing outwardly under the pressure of the springs I, so that the respective pawls e, being thus released, are thrust into engagement with their ratchets f by the springs e², and the rotary 85 movement of the motor-armature and shaft is transmitted through the counterpart trains of gearing, hereinbefore described, to the respective arbors of the several movements and the springs thereof rewound.

To prevent the overwinding of the respective springs by the operation of the parts above described, each of the clock-movements is conveniently provided with stop mechanism consisting of a stud j, fixed in relation with the pawl-disk E, so as to rotate therewith and engage the notches of the stop-wheel J, shifting the latter one notch at each 100 rotation of the pawl-disk E until the arm J' of said stop-wheel J slides over the extremity e³ of the pawl e and disengages the latter from the ratchet f. The wheels J are counterpart 105 and conveniently mounted in pairs in brackets K, extending from the casing X between adjoining clock-movements. Accidental rotation of the wheels J is prevented by the pins k, which register with sockets k' in said 110 wheels and are thrust therein by springs k². If the respective gearing-trains are synchronously operated and the respective pawls e 115 maintained in similar angular relation with their respective movements, as shown in Fig. 4, it is obvious that the counterpart stop mechanisms above described will be simultaneously operated. It is to be noted, however, that, as indicated in Fig. 8, said stop mechanisms are entirely independent of each other and may therefore be operated at different 120 times in accordance with the particular angular relation of the parts.

In the form of our invention shown in Figs. 2 and 7 the armature A⁸ of the motor A is arranged to rotate without longitudinal reciprocation, and the frame G is provided with springs I', which tend to thrust said frame inwardly and disengage the pawls e, as indicated in Fig. 7. In this form of our invention the frame G is rocked outwardly and the 125 pawls e released by means of the electromagnet D, which is opposed to the arm G³ of the frame G, which serves as an armature for it.

As a convenient adjunct to the elements of

our invention above described it is desirable to provide mechanism whereby the extent of the rewinding action of the parts may be indicated or reported exterior to the vault or safe. We have therefore shown in Fig. 4 the terminals L L' of an electric circuit, which extends exterior to said vault and is adapted to be closed within the latter by means of the circuit-closer M. Said circuit-closer M comprises a disk, upon which are fixed four studs m, adapted to successively encounter the spring-terminal L and effect the contact of the latter with the terminal L'. The gear-wheel m', fixed upon said circuit-closer M, engages with the gear-wheel N, mounted for rotation upon the frame O, which is insulated from the casing X. The gear N' is in fixed relation with the gear N, and both of said gears are rotated by the engagement of the former with the worm A⁸ upon the shaft A⁴. The ordinary clock-movement for a time-lock is so proportioned that one complete revolution of its main arbor winds the main-spring sufficient to operate the clock-movement for a period of ten and four-fifths hours, and, as illustrated, the train of gearing leading to the circuit-closer M is so proportioned that the studs m complete the circuit through the terminals L L' at intervals, indicating that the clock-movements have been rewound the extent sufficient for one-half hour's operation thereof. It will be understood that the closing of the circuit at the terminals L L', as above described, may be utilized to operate any convenient form of indicating device exterior to the vault.

Although we prefer to employ an electric motor to actuate our rewinding mechanism, as above described, it is to be understood that we do not desire to limit ourselves to the use of such a motor in combination therewith, as it is obvious that the precise nature of the motor used is not of the essence of our invention. Moreover, we do not desire to limit ourselves to the details of construction above described, as it is obvious that various modifications may be made therein without departing from the spirit of our invention.

We claim—

- 50 1. The combination with a time-lock for a vault or safe, of a motor adapted to rewind the spring of the time-lock clock-movement, normally-disengaged clutch mechanism, arranged to operatively connect said motor and said spring, and means, distinct from said clock-movement, arranged to simultaneously initiate the operation of said motor and the engagement of said clutch mechanism, substantially as set forth.
- 60 2. The combination with a time-lock for a vault or safe, of a motor adapted to rewind the spring of the time-lock clock-movement, normally-disengaged clutch mechanism, arranged to operatively connect said motor and said spring, and means, exterior to the vault, arranged to simultaneously initiate the operation of said motor and the engagement of

said clutch mechanism, substantially as set forth.

3. The combination with a time-lock for a vault or safe, of a motor adapted to rewind the spring of the time-lock clock-movement, normally-disengaged clutch mechanism, arranged to operatively connect said motor and said spring, and means, comprising an electric circuit, extending exterior to the vault, arranged to simultaneously initiate the operation of said motor and the engagement of said clutch mechanism, substantially as set forth. 70

4. In a time-lock, the combination with a clock-movement, of a motor adapted to rewind the spring of said movement, rewinding mechanism adapted to operatively connect said motor and said spring, and comprising a normally-disengaged clutch, a movable detent to retain said clutch in disengaged position, and coöperative means, independent of said clock-movement, to release said detent and engage said clutch, substantially as set forth. 85

5. In a time-lock, the combination with a plurality of clock-movements, of a motor adapted to rewind the springs of said movements, rewinding mechanism operatively related to said motor; common to all of said clock-movements but normally disconnected therefrom, clutches forming part of the rewinding mechanism, arranged to independently engage the respective clock-movements, movable detents to normally retain the respective clutches in disengaged position, and coöperative means, independent of said clock-movements, to release said detents and engage the respective clutches, substantially as set forth. 95

6. In a time-lock, the combination with a plurality of clock-movements, of a motor adapted to rewind the springs of said movements, rewinding mechanism operatively connected with said motor and comprising a shaft provided with worm-gearing trains leading to the respective clock-movements, normally-disengaged clutches in the respective trains, and coöperating means, independent of said clock-movements, to engage said clutches and actuate said motor, substantially as set forth. 100

7. In a time-lock, the combination with a clock-movement, of a motor adapted to rewind the spring of said movement, rewinding mechanism operatively connected with said motor and comprising a clutch member, a clutch member fixed upon the main arbor of said clock-movement, opposed to the clutch member of the rewinding mechanism, means to normally disengage said clutch members, and means, independent of said clock-movement, to engage said clutch members, substantially as set forth. 115

8. In a time-lock, the combination with a clock-movement, of a motor adapted to rewind the spring of said movement, a shaft operatively related to said motor and pro-

vided with a worm, a worm-gear engaged with said worm and loosely mounted concentric with the axis of the main arbor of said clock-movement, a ratchet-clutch member upon 5 said worm-gear, a pawl-bearing, fixed upon the main arbor of said clock-movement, a pawl mounted in said bearing and adapted to engage said ratchet-clutch, a detent to normally disengage said pawl from said ratchet- 10 clutch, and means independent of said clock-movement to release said detent, substantially as set forth.

9. In a time-lock, the combination with a 15 clock-movement, of mechanism adapted to rewind the spring of said movement, and stop mechanism to prevent the overwinding of said spring, comprising means to automatically disengage said rewinding mechanism at

the proper period in its operation, substantially as set forth. 20

10. In a time-lock the combination with a 25 clock-movement, of a motor adapted to rewind the spring of said movement, rewinding mechanism operatively connected with said motor, and comprising a shaft provided with a worm-gearing train leading to said clock-movement, a normally - disengaged clutch in said train, and means independent of said clock-movement to engage said clutch, substantially as set forth.
